TAPE MEASURE

André Quenot, Besançon, France, assignor to the firm of
Etablissements Quenot & Cie. S.a.r.l., Besançon, France

Filed Nov. 24, 1964, Ser. No. 82,761

Claims priority, application France May 29, 1964

Term of patent 14 years

(Cl. D52—1)

FIG. 1

FIG. 2

FIG. 4

FIG. 3

FIG. 1 is a side elevational view of a tape measure, showing my new design;

FIG. 2 is a top plan view thereof;

FIG. 3 is an end view thereof;

FIG. 4 is a side perspective view thereof.

The side and end opposite those shown in FIGURES 1 and 4 are substantially identical to those illustrated. The bottom view is plain having no design characteristics.

I claim:

The ornamental design for a tape measure, as shown and described.
